UNITED STATES PATENT OFFICE.

RUSSELL B. PERKINS, OF MERIDEN, CONNECTICUT, ASSIGNOR TO E. MILLER & CO., OF SAME PLACE.

IMPROVEMENT IN GLOBE-HOLDERS FOR LAMPS.

Specification forming part of Letters Patent No. 159,608, dated February 9, 1875; application filed December 16, 1874.

To all whom it may concern:

Be it known that I, RUSSELL B. PERKINS, of Meriden, in the county of New Haven and State of Connecticut, have invented a new Improvement in Globe-Holders for Lamps; and I do hereby declare the following, when taken in connection with the accompanying drawings and the letters of reference marked thereon, to be a full, clear, and exact description of the same, and which said drawings constitute part of this specification, and represent, in—

Figure, 1 a perspective view of the holder; Figs. 2 and 3, vertical sections of the holder as applied to different burners.

This invention relates to an improvement in the article of lamp furniture known as a "globe-holder"—that is, the ring which is attached to or placed over a burner to support a globe-shade.

As the construction of lamps is various, it has been the usual practice to make holders fitted for each particular class of burner—as, for instance, the "sun-burner," and other burners which have an internal support for the chimney some distance above the chimney-rest, requiring a very different construction from the class which have external springs extending up from the chimney-rest outside the chimney. Hence, manufacturers and dealers are obliged to keep a variety of holders in order to meet the demand for the great variety of burners, many of which are required to be furnished with globe-holders.

The object of this invention is to construct a universal globe-holder, or one which is adapted to the various constructions of burners; and it consists in a holder formed with a rest for the globe, and with an internal ring constructed with downward-projecting clasps upon its lower edge to sit over the chimney-rest, and with notches in its upper edge to pass over the external vertical springs of the burner, as more fully hereinafter described.

A is the globe-rest, formed in the usual manner to receive the lower rim of the globe.

Within this rest is a ring, B, its internal diameter being substantially that of the exterior of the chimney. On the lower edge of this ring B are formed several tongues, a, projecting downward, and so as to pass over the outer edge of the chimney-rest, it being understood that the diameter of the chimney-rest is common to all burners of the classes for which the globe-holder is intended. In the upper edge of the ring B are notches d, corresponding to the vertical springs C of the class of burners which have outside springs, as seen in Fig. 2.

For the "sun-burner," and burners of that class, such as seen in Fig. 3, the holder is passed over the deflector, springs D, and set down onto the chimney-rest E, as seen in Fig. 3, the tongues a passing down and clasping over the edge of the rest.

For burners of the other class—that is, with outside springs—the holder is placed over the burner, the ring B within the spring C, but so that the notches d will be in line with the springs, and then pressed down, the springs yielding for the purpose, to sit upon the rest E, as in Fig. 2, the tongues a passing down over the edge of the rest, the same as in the sun-burner; but in this case the springs C fall back into the notches d, thus leaving the springs as free as if the holder were not present.

By constructing the holder with both the tongues a and notches d, I produce a globe-holder common to all burners using the same chimney.

I claim—

The herein-described globe-holder, consisting of the outer ring or globe-rest, A, and the inner ring, B, provided with the tongues a upon its lower edge, and the notches d upon its upper edge, substantially as specified.

RUSSELL B. PERKINS.
